PORTABLE TYPEWRITER

Ettore Sottsass, Jr., 14 Via Manzoni,
20121 Milan, Italy

Filed Nov. 3, 1969, Ser. No. 19,893

Claims priority, application Italy May 3, 1969

Term of patent 14 years

Int. Cl. D18—01

U.S. Cl. D64—11

Fig. 1

Fig. 2

FIG. 1 is a front perspective view of a portable typewriter showing my new design as it appears in closed position;

FIG. 2 is a rear perspective view thereof;

FIG. 3 is an exploded front perspective view thereof as it appears with the typewriter removed from the case; and

FIG. 4 is an exploded rear perspective view thereof.

I claim:

The ornamental design for a portable typewriter, substantially as shown and described.
